CLAIM

The ornamental design for a computing device as shown and described.

DESCRIPTION

FIG. 1 is a front perspective view of a computing device showing our new design;

FIG. 2 is another front perspective view of the computing device with an encircled portion showing the enlargement area of FIG. 9;

FIG. 3 is a front view thereof;

FIG. 4 is a rear view thereof;

FIG. 5 is a right side view thereof;

FIG. 6 is a left side view thereof;

FIG. 7 is a top view thereof;

FIG. 8 is a bottom view thereof; and

FIG. 9 is an enlarged view of an encircled portion of the computing device labeled 9 in FIG. 2; and,

FIG. 10 is a bottom perspective view of the computing device.

The even-length broken lines in the drawings depict portions of the computing device that form no part of the claimed design. The dash-dot-dash broken lines in FIGS. 2 and 9 encircling portions of the computing device illustrated in enlargements form no part of the claimed design.
